UNITED STATES PATENT OFFICE.

WILLIAM P. TURNER, OF GREENSBORO, NORTH CAROLINA.

CHECK-BOOK HOLDER.

Application filed October 3, 1923. Serial No. 666,372.

To all whom it may concern:

Be it known that I, WILLIAM P. TURNER, a citizen of the United States, residing at Greensboro, in the county of Guilford and State of North Carolina, have invented certain new and useful Improvements in Check-Book Holders, of which the following is a specification, reference being had to the accompanying drawings.

10 This invention relates to check book holders and more particularly to a device for holding small folding check books flat so as to facilitate the writing of checks thereon.

15 An important object of the invention is to provide a device of this character which is simple in its construction and arrangement, which may be very readily applied to the check book and which when so applied will 20 in no manner interfere with the operation of writing the check.

A still further object of the invention is to provide a device of this character which normally holds the check in the open position but locks the same in such open position and which likewise serves to lock the check book in a closed position so as to eliminate to a great extent the opening of the check book in the pocket which often results in 25 small papers, cards or the like being inadvertently inserted therein.

These and other objects I attain by the construction shown in the accompanying drawings wherein for the purpose of illustration is shown a preferred embodiment of 30 my invention and wherein:—

Figure 1 is a perspective view showing a check book having my invention applied thereto;

40 Figure 2 is a front elevation of the appliance in position upon the open check book;

Figure 3 is a plan view thereof, the check book being in the closed or folded position;

45 Figure 4 is a perspective of the combined guide and holding plate; and

Figure 5 is a perspective of the mounting for the holding arm showing the holding arm in one position in solid lines and in 50 the second position in dotted lines.

Referring now more particularly to the drawings, the numeral 10 designates generally a folding check book designed in its construction to fold along the transverse line at its center, as indicated at 11, so that the single backing strip provides the com-

plete cover for the check book. The covers employed with this type of check book are usually flexible in themselves and constructed of some cheaply and readily produced material such as fibre. Due to the fact that the book remains in the folded position during the majority of its life it becomes fixed in such folded position and has a tendency to refold when opened necessitating holding during the writing of a check.

In accordance with my invention I secure to the back at one edge thereof and adjacent the fold or bend 11 a plate 12 which lies flatly against the surface of the book and which is provided with a flange 13 overlying the edges of the checks 14 of the book and preferably of less width than the thickness of these checks when doubled or folded. At the opposite side of the bend or fold I secure to the same edge of the back a second plate 15 which likewise has a flange 16 extending over the edges of the checks. One side of this flange has a reverted extension 17 paralleling the flange in spaced relation thereto and preferably having its free end abutting the plate. The opposite side of the flange is provided with a downturned finger 18. The plate 15 and its associated parts are struck from a single sheet of resilient material and the finger 18 is so formed in its construction that it has a tendency to move toward the back of the book and accordingly presses the checks at this side of the fold 11 against such back.

Pivotedly connected to the flange 13 adjacent the plate 12 is one end of a locking arm 19 which is of a width less than the width of the flange 13 and which has its free end portion directed through the loop or eye 20 formed by the flange 16 and its reverted portion 17. Intermediate its ends the arm 19 is formed with a finger 19^a similar to the finger 18. This finger is formed integrally with the locking arm and extends at right angles thereto to engage the checks, when the book is open, at a point intermediate the flange 13 and the flange 16. Adjacent its free edge the flange 13 has formed thereon by punching or the like detents or stops 21 which when the edges of the bar 19 are parallel with the plate 12 resist movement of the bar with respect to the plate 10 and accordingly since the free end of this bar is engaged in the loop 20 relative move-

ment of the portions of the check book lying at opposite sides of the bend 11.

From the foregoing it will be seen that a device constructed in accordance with my invention may be very cheaply produced and very readily applied to the check book and that when so applied will in no manner interfere with the writing of the check, since the spring fingers 18 and 19^a may be so positioned that they do not extend upon any of those spaces provided in the check for filling out. Such a device will furthermore in no way interfere with the handling or folding of the book and will not render the check book cumbersome or uncomfortable when placed in the pocket.

It will be obvious that the construction hereinbefore set forth is capable of a certain range of change and modification without in any manner departing from the spirit of my invention and I accordingly do not limit myself to such specific structure except as hereinafter claimed.

I claim:—

1. In combination with a folding member having a back and leaves, of a plate secured to one edge of the back adjacent the fold and a second plate secured to the same edge of the back at a point spaced from the fold 30 at the opposite side of the fold from the first named plate, means carried by the last named plate for maintaining the leaves of the member in engagement with the back, and a connection between the plates pivoted to one of said plates and slidably engaged with the other of said plates maintaining the sections of the back in aligned or opposed relation, one of said plates having means resisting shifting of the connection 35 from either of said positions to the other position.

2. In combination with a folding member having a back and leaves, of a plate secured to one edge of the back adjacent the fold 45 and a second plate secured to the same edge of the back at a point spaced from the fold at the opposite side of the fold from the first named plate, means carried by the last named plate for maintaining the leaves of the member in engagement with the back, and a connection between the plates maintaining the sections of the back in aligned or opposed relation, comprising a bar pivotally connected to the first named plate and directed through a loop in the second named plate.

3. In combination with a folding member having a back and leaves, of a plate secured to one edge of the back adjacent the fold 60 and a second plate secured to the same edge of the back at a point spaced from the fold

at the opposite side of the fold from the first named plate, means carried by the last named plate for maintaining the leaves of the member in engagement with the back, a connection between the plates maintaining the sections of the back in aligned or opposed relation, comprising a bar pivotally connected to the first named plate and directed through a loop in the second named plate, and means upon the first named plate for coacting with the bar resisting movement of the bar from either of said positions.

4. In combination with a folding member having a back and leaves, of a plate secured to one edge of the back adjacent the fold and a second plate secured to the same edge of the back at a point spaced from the fold at the opposite side of the fold from the first named plate, means carried by the last named plate for maintaining the leaves of the member in engagement with the back, a connection between the plates maintaining the sections of the back in aligned or opposed relation, comprising a bar pivotally connected to the first named plate and directed through a loop in the second named plate, and means upon the first named plate for coacting with the bar resisting movement of the bar from either of said positions, the first named plate embodying a flange overlying the edges of the leaves of the check book and to which said bar is pivoted to swing in a plane parallel with such edges and pressed detents in said plate and disposed at that side of the flange outwardly of the bar from the plate when the bar is in either of said positions.

5. In combination with a folding member having a back and leaves, of a plate secured to one edge of the back adjacent the fold and a second plate secured to the same edge of the back at a point spaced from the fold at the opposite side of the fold from the first named plate, means carried by the last named plate for maintaining the leaves of the member in engagement with the back, and a connection between the plates maintaining the sections of the back in aligned or opposed relation, comprising a bar pivotally connected to the first named plate and directed through a loop in the second named plate, said bar being provided intermediate the loop of the second plate and the first named plate with a finger flatly engaging the leaves of the member when in open or closed position.

In testimony whereof I hereunto affix my signature.

WILLIAM P. TURNER.
